FORK

Richard C. Gavette, Hampton, N.H., assignor to
Gorham Corporation, Providence, R.I.

Filed May 19, 1964, Ser. No. 80,065

Term of patent 14 years

(Cl. D54—12)

FIGURE 1 is a front elevational view of a fork, showing my new design,

FIGURE 2 is a side elevational view thereof, and

FIGURE 3 is a rear elevational view of the fork shown in FIGURE 1.

The essential features of my design reside in the full line portions of the drawing.

The design is intended for use on sets comprising forks, spoons and knives and similar articles of flatware.

I claim:

The ornamental design for a fork, as shown and described.
